CLAIM

The ornamental design for purse organizer, as shown and described.

DESCRIPTION

FIG. 1 is a front, right and top perspective view of purse organizer, showing my design.

FIG. 2 is a rear, left and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1 comprising a zip; and,

FIG. 10 is an exploded view of the purse organizer of FIG. 1.

The broken lines shown in the drawings are included for the purpose of illustrating portions of the purse organizer that form no part of the claimed design.

1 Claim, 10 Drawing Sheets
